HAIR BRUSH CLEANER

Gerald E. Klinge, 5637 Dunk Drive, Norman H. Vogel, Jr., 326 E. Bangor Drive, and Norman H. Vogel, Sr., 262 E. Bangor Drive, all of Indianapolis, Ind.

Filed Nov. 19, 1963, Ser. No. 324,671
5 Claims. (Cl. 15—310)

This invention relates generally to cleaning and sanitizing and sterilizing devices for beauty shops and barber 10 shops, and more particularly to a device for cleaning, sanitizing, and sterilizing hair brushes and the like.

In beauty shops, it is necessary for the proprietors to maintain a substantial supply of hair brushes and combs. This is necessitated largely by the fact that it is difficult to remove hair thoroughly from hair brushes and it is a time consuming task. Typically, it is done by raking a comb through the hair brush and then removing the hair from the comb by hand. Not only is it time consuming but it is also unsanitary. Particularly is this true because of the resiliency of bristles of a brush and their tendency to throw hair and particles when released as the comb is passed through the bristles.

It is, therefore, a general object of the present invention to provide a device capable of contributing substantially to the health and sanitary standards attainable in barber shops and beauty parlors.

A further object is to provide a device by which hair and other debris can be removed readily, quickly, conveniently, and under sanitary conditions.

A further object is to provide a device achieving the foregoing objects and facilitating the sterilization and drying of brushes.

Described briefly, a typical embodiment of the present invention incorporates a housing having two compartments, with an air pump in one compartment and a collection bag in the other compartment. The air pump discharges into a sterilizer unit and draws air through the collection bag to which air is admitted by a nozzle arrangement.

A cover is provided on the bag containing compartment and serves as a mount for the nozzle. The bag has a nozzle mounting arrangement receivable on the portion of the nozzle projecting into the second compartment and readily mounted to and removed from the projecting nozzle portion. The cover to which the nozzle is mounted is movable to a position exposing to the outside the bag and mounting fitting to facilitate installation and removal.

The entrance of the nozzle is shaped and provided with notches and a comb fitting to not only effectively and completely remove debris from hair brushes but also to facilitate the handling of a hair brush in passing it across the nozzle.

The full nature of the invention will be understood from the accompanying drawings and the following description and claims.

FIG. 1 is a perspective view of a typical embodiment of the present invention.

FIG. 2 is a section therethrough taken along the line 2—2 and viewed in the direction of the arrows.

FIG. 3 is a section illustrating the bag and nozzle mounting arrangement, the section being taken along the line 3—3 in FIG. 2 and viewed in the direction of the arrows.

FIG. 4 is a section taken along the line 4—4 in FIG. 1 and viewed in the direction of the arrows, this section illustrating one manner of mounting the cover to the main portion of the housing and sealing it thereto.

FIG. 5 is an enlargement of a portion of FIG. 2.

Referring to the drawings in detail, the housing includes parallel upstanding side walls 12 and 13, and parallel upstanding end walls 14 and 16. The bottom 17 extends

2

the entire length and width of the housing or cabinet, whereas the principal portion of the top 18 extends only part of the length of the cabinet. A removable cover member or lid 19 completes the exterior of the main housing, and is disposed on an incline upwardly from the front of the unit toward the rear of the unit.

A bulkhead 21 is provided in the housing dividing the interior thereof into two major compartments 22 and 23. In the compartment 22 there is a combination motor and blower 24 to serve as an air pump. The specific arrangement of the motor and blower is not important to the invention so long as the air pump comprises means for moving air. The air pump has an inlet duct 25 and an outlet 26. The inlet is provided with a flange 27 engaging a plate 28. The bulkhead 21 and plate 28 sandwich a screen 29 therebetween and the bulkhead has an aperture 31 therein communicating through the screen with the aperture 32 in the plate 28 which communicates with the interior of the duct 25. Air flow can thereby be established by the pump through the aperture 31, screen 29, and aperture 32. In this manner, air is drawn from the chamber 23 through the pump and discharged through the outlet 26. Assuming that the chamber 23 were completely closed, a very high vacuum could be established therein by the pump operation. As a matter of fact, this feature is utilized by mounting a nozzle 33 on the cover 19.

The cover 19 is generally rectangular in form and has a mitered surface 34 along the upper marginal edge thereof and a mitered surface 36 along the lower marginal edge thereof. The lower surface 37 is planar and extends from a horizontal edge 38 (FIG. 5) down to the horizontal edge 39. At the edge 39, a step 41 is provided leaving a sealing surface 42 which rests on the sealing member 43 which is secured to the mitered upper end surface 44 of the front wall 16.

As shown best in FIG. 4, a similar step 46 is provided adjacent the side margin 47 of the lid. A sealing surface 48, parallel to the surface 37, between the margin 47 and step 46 rests upon the gasket 49 which is secured by adhesive or other suitable means to the upstanding side wall 12. An identical construction is provided at the opposite side wall.

The upper fixed portion 18 of the housing overhangs the mitered upper marginal surface 34 of the lid, and the step 41 can engage the upper edge of the mitered upper surface 44 of the front wall 16 of the housing. Therefore, the lid can be snapped into place by first inserting the surface 34 under the overhanging top portion at 51, and pressing the lid rearwardly and upwardly against the gasket 52 until it is possible to snap the lower edge 39 of the step 41 over the upper edge of the upper surface 44 of the front wall. The lid will then remain securely in place, being sealed all around by the various gaskets, just described. Therefore, unless a nozzle is provided in the lid or some other aperture were provided in the compartment 23, there would be no place for air to enter the compartment 23 when the pump is operating.

According to an important feature of the present invention, the nozzle 33 is mounted to the lid. This nozzle has a generally rectangular configuration as shown in FIG. 1, and is mounted by means of the flange 53 resting on the gasket 54. Four screws 55 may be provided to secure the flange to the lid. In lieu of the gasket illustrated, gasket cement or a perfect fit can be provided, the intention being that no air flow through the generally rectangular aperture 56 in the lid be possible, other than that passing through the interior of the nozzle.

As best observed in FIG. 2, the generally rectangular inlet opening 57 of the nozzle inlet portion 58 is preferably disposed at a steeper slope than the slope of the inclined lid to which the nozzle is mounted. This facilitates

drawing of a brush across the nozzle in the direction of the arrow 59 which is downwardly and toward the front of the housing.

A comb element 61 is mounted on the inside surface of the nozzle by means of a rivet 62 or the like, and includes comb teeth spaced along the lower marginal edge 63 of the inlet opening. These teeth begin in a direction perpendicular to the upper and lower surfaces of the cover, this being parallel to a plane 64 equidistant between the upper and lower inside faces 66 and 67 respectively of the nozzle. The teeth then curve upwardly as at 68, and their distal ends terminate immediately adjacent the imaginary plane 64. These comb tips are at an elevation slightly below the inner upper marginal edge 69 of the inlet opening.

Notches 71 are spaced along the upper marginal edge of the inlet opening of the nozzle. These notches are typically engaged by some of the bristles of a brush as it is drawn across the upper edge in the downward direction indicated generally by the arrow 59. Because some of the bristles do not become engaged by the notches but are engaged by the upper edge 72 directly, not all of the bristles are bent upwardly at the same time, thus achieving a better and random spreading of the bristles as the brush is drawn across the nozzle opening, thereby achieving a better removal of debris from within each group of bristles. The comb is quite effective to remove hair and other debris, and the upward curve of the comb keeps all hair and debris removed directly in line with the air flow into the nozzle whereupon all debris is pulled into the nozzle without any falling outside of the nozzle. It is usually desirable to have the width of the nozzle inlet between the side margins 73 and 74 thereof to be approximately equal to or less than the average width of brushes to be cleaned by the device.

As previously mentioned, a debris collection bag 76 is provided in the chamber 23. An important feature of this invention is the means of mounting the bag to the nozzle to retain it securely in place and yet facilitate installation and removal thereof. To this end, a generally rectangular mounting board 77 is secured by adhesive or other suitable means to the surface 79 of the bag. This may be the end of a somewhat conventional vacuum cleaner dirt collection bag, the bag 76 being composed of the same or a similar type of air permeable material. The end of the bag may be of rather conventional construction. However, it has a generally rectangular aperture 81 therein. The mounting of the board 77 to the end of the bag is preferably by means of adhesive because an air seal is thereby obtained therebetween.

The board 77, which is typically made of a fibrous material, has a generally rectangular aperture 82 therein registering with the aperture 81 in the end of the bag. As is apparent in FIGS. 2, 3, and 5, the upper and lower margins 83 and 84, respectively of the board extend well beyond the margins 86 and 87 of the bag.

A retainer board 88 is mounted to the upper surface of the mounting board 77, and both of these boards may be made of a fibrous material such as heavy paperboard approximately $\frac{1}{10}$ inch thick, for example. If desired, the boards could be plastic or metal. A feasible means of attaching the two boards together is by means of an adhesive, and a generally rectangular rubber gasket 89 is sandwiched therebetween adjacent the aperture 82 in the board 77. This gasket has a generally rectangular aperture 91 therein embracing the entire outer perimeter of the portion of the nozzle extending through the aperture 56 in the lid 19. This is illustrated in FIG. 3 and in FIG. 5, the outer perimeter of the lower or outlet portion of the nozzle being designated by the reference numerals 92, 93, 94, and 96.

A step 97 is provided all the way around the perimeter of the lower portion of the nozzle and at a point a short distance above the nozzle outlet opening 98. This step provides a surface over which the rubber gasket 89 can snap during installation of the bag on the nozzle. In

effect, a retaining flange 99 extends entirely around the outlet opening of the nozzle, the dimensions of this flange being just slightly smaller than the interior dimensions of the aperture 101 in the board 88. Also, it is to be noted that the dimension between the step 97 and the underside 102 of the upper flange of the nozzle is such that a space 104 is provided between the lower surface 37 of the lid and the upper face 106 of the board 88.

The advantages of this novel bag mounting arrangement will now become apparent. By providing an aperture 101 in the board 88 approximately the same size but just slightly larger than the flange 99 at the lower or outlet end of the nozzle, the board 88 can be aligned with the lower end of the nozzle when the bag is pushed onto the nozzle in the direction of the arrow 107. By so doing, the aperture in the rubber gasket 89 is centered on the nozzle flange and will not be excessively stretched in any direction during the installation of the bag. Moreover, once the inner edges or lips of the gasket has snapped over the step 97, the inner face 108 of the board 88 immediately adjacent the aperture therein provides a brace or support for the rubber and prevents the bag from being blown off the nozzle when the bag becomes comparatively full of debris. The proper dimension accommodating the space 104 facilitates installing the bag or pushing it upwardly sufficiently toward the surface 37 that complete snapping of the gasket over the step all the way around the gasket aperture is readily achieved.

By providing an appropriate thickness of the board 88, the upper surface 109 of the board 77 is appropriately spaced at all times from the inside face 37 of the lid to enable the projection of fingertips into the space 111 to facilitate the removal of the bag by pulling away from the lid in the direction of the arrow 112. By extending the outer margins of the board 77 beyond the outer margins 87 and 86 of the bag, the application of the thumbs to the board without puncturing or otherwise encountering the bag during installation of the bag is possible to facilitate the mounting of the bag on the nozzle.

By having the bag disposed at an angle with respect to the screen 29 against which it is usually pulled during operating of the pump, debris tends to collect in the lower frontal area of the bag as indicated by reference numeral 113 in FIG. 2. This means, that until the bag is quite full there will continue to be an adequate high flow of air through the bag into the pump and consequently through the nozzle into the bag. This achieves a continuous high vacuum for a long period of time without the necessity of removing the bag. As shown in FIG. 1, a sterilizer apparatus 116 is mounted to the right-hand wall of the box. This apparatus includes a lid 117 accommodating insertion of brushes and combs into the apparatus. The apparatus can be one of a variety of those well known in the art and readily available on the market. A duct 118 is provided between the sterilizer apparatus and the pump outlet 26 of FIG. 2 whereby the air discharged from the pump is forced into the sterilizer. This is useful to dry brushes and combs. Air outlet from the sterilizer can be attained by the openings 119 in the side thereof. It will be recognized that a variety of sterilizers can be employed according to the novel concept of this invention.

In the foregoing description, certain materials and specific configurations have been mentioned and illustrated. These are, however, for the purposes of illustration only, as other material and configurations may also be found to be satisfactory and yet within the scope of the present invention.

While the invention has been disclosed and described in some detail in the drawings and foregoing description, they are to be considered as illustrative and not restrictive in character, as other modifications may readily suggest themselves to persons skilled in this art and within

the broad scope of the invention, reference being had to the appended claims.

The invention claimed is:

1. A hair brush cleaner comprising: a case having first and second compartments therein, with said second compartment having side walls with inclined upper margins, and a roof overhanging the upper ends of said inclined margins; an air pump in said first compartment and having an inlet communicating with said second compartment and an outlet communicating with a sterilizer and drier mounted to said case whereby air is drawn from said second compartment and discharged through said sterilizer and drier to atmosphere; a generally planar sloping roof member on said second compartment and having an aperture therein and having a step resting on an upper margin of an end wall of said second compartment; means sealing said roof member to said end wall, side walls, and said roof; a nozzle in said roof member and having a tubular inlet portion of generally rectangular cross section and disposed at the exterior of said case and a tubular outlet portion of generally rectangular cross section and extending through said aperture into the said second compartment and having a generally rectangular outlet opening, the inlet portion having a generally rectangular inlet opening disposed at an angle with respect to the plane of said roof member, the upper margin of said inlet opening having a plurality of notches spaced therealong, the outer surface of said outlet portion having a step therearound adjacent said outlet opening and being larger on the side of the step near the outlet opening of said outlet portion than on the side of the step near the inlet opening of said inlet portion; a plurality of comb teeth spaced along the lower margin of said inlet opening and first extending perpendicular to the plane of said roof member and then extending curvilinearly toward distal ends above said inlet opening of said inlet portion and at an elevation below the upper margin of said inlet opening, the distal ends of said teeth lying adjacent an imaginary plane normal to the plane of said roof member, said imaginary plane being equidistant from said upper and lower margins; and an air permeable refuse collection bag in said second compartment, said bag having a single and generally rectangular opening receiving the said outlet portion of said nozzle; a first generally planar board sealingly secured to said bag and having a generally rectangular aperture in registry with said opening in said bag, said board having marginal portions extending beyond opposite margins of said bag to facilitate installation and removal of said bag on said outlet portion; a second board mounted on the upper face of said first board and having an aperture sized to fittingly receive said larger surface of said nozzle outlet portions; and a flexible seal having a portion sandwiched between and sealingly secured to said boards and having a portion sealingly engaging the perimeter of said outlet portion between said step and said roof member, the aperture in said second board having dimensions greater than the aperture in said first board to accommodate flexing of said perimeter engaging portion of said seal more easily in a direction toward said bag than away from said bag to facilitate attachment of said bag to said nozzle and prevent unintentional separation of said bag from said nozzle, the upper surface of said first board being spaced from the inside face of said roof member to accommodate insertion of fingertips therebetween to facilitate removal of said bag from said nozzle outlet portion; means sealing said nozzle to said roof member; said roof member being movable to open said second compartment and expose the inside face of said roof member to facilitate installation and removal of said bag on said nozzle outlet portion.

2. A hair brush cleaner comprising: a case having first and second chambers therein; an air pump in said first chamber and having an inlet communicating with said second chamber and an outlet discharging to atmosphere

75

whereby air is drawn from said second chamber and discharged to atmosphere; a movable member on said case forming a margin of said second chamber and having an aperture therein; a nozzle in said member and having a tubular inlet portion beginning with an inlet opening disposed at the exterior of said case, and said nozzle having a tubular outlet portion extending through said aperture and terminating with an outlet opening in said second chamber; a plurality of comb teeth spaced along a margin of said inlet opening and extending in front of a portion of said inlet opening; and an air permeable refuse collection bag in said second chamber, said bag having an opening receiving the said outlet portion of said nozzle; a board secured to said bag and having an aperture in registry with said opening in said bag, said board having marginal portions extending beyond opposite margins of said bag to facilitate installation and removal of said bag on said outlet portion; and a flexible seal sealed to said bag and sealingly engaging the perimeter of said outlet portion, the exterior of said nozzle being sealed to said movable member, said movable member being movable to open said second chamber and expose the said collection bag to facilitate installation of said bag on said nozzle outlet portion and removal of said bag from said nozzle outlet portion.

3. In a hair brush cleaner, the combination comprising: a case having a compartment therein; an air pump having an inlet communicating with said compartment and an outlet discharging to atmosphere whereby air is drawn from said compartment and discharged to atmosphere; a movable member on said case forming a margin of said compartment and having an aperture therein; a nozzle in said member and having an inlet portion beginning with an inlet opening disposed at the exterior of said case, and said nozzle having an outlet portion extending through said aperture and having an outlet opening in said compartment; a comb extending in front of a portion of said inlet opening; and an air permeable refuse collection bag in said compartment, said bag having an opening receiving the said outlet portion of said nozzle; a board secured to said bag and having an aperture in registry with said opening in said bag, said board having a marginal portion extending beyond a margin of said bag to facilitate installation and removal of said bag on said outlet portion; and a flexible seal sealed to said bag and sealingly engaging the perimeter of said outlet portion, said movable member being movable to open said compartment and expose the said collection bag to facilitate installation of said bag on said nozzle outlet portion and removal of said bag from said outlet portion.

4. In a hair brush cleaner, the combination comprising: a case having a compartment therein; an air pump having an inlet communicating with said compartment and an outlet discharging to atmosphere whereby air is drawn from said compartment and discharged to atmosphere; an aperture in said case; a nozzle having an inlet portion beginning with an inlet opening disposed at the exterior of said case, and said nozzle having an outlet portion extending through said aperture and having an outlet opening in said compartment; a plurality of comb teeth extending in front of a portion of said inlet opening; and refuse collection means including an air permeable refuse collection bag in said compartment, said bag having an opening receiving the said outlet portion of said nozzle, board means secured to said bag adjacent said opening in said bag, said board having marginal portions extending beyond opposite margins of said bag to facilitate installation and removal of said bag on said outlet portion, and a flexible seal sealed to said bag and having a portion sealingly engaging and slidably on the perimeter of said outlet portion, and means on said outlet portion engageable with a portion of said collection means to retain said collection means on said outlet portion.

5. In a hair brush cleaner, the combination comprising: a case having a compartment therein; an air pump having

an inlet communicating with said compartment and an outlet discharging to atmosphere whereby air is drawn from said compartment and discharged to atmosphere; an aperture in said case; a nozzle having an inlet portion having an inlet opening disposed at the exterior of said case, and said nozzle having an outlet portion extending through said aperture and having an outlet opening in said compartment; a plurality of comb teeth extending in front of a portion of said inlet opening; and refuse collection means including a container having an air permeable portion in said compartment, said container having an opening receiving the said outlet portion

5 of said nozzle, and a flexible seal sealed to said container and having a portion sealingly engaging the perimeter of said outlet portion, and means engageable with a portion of said collection means to retain said collection means on said outlet portion.
